ELECTRIC BATTERY LANTERN

Herbert J. Ashe, % The H. J. Ashe Co. Inc.,
South Norwalk, Conn. 68509

Filed June 10, 1968, Ser. No. 12,277

Term of patent 14 years

U.S. Cl. D48—24
Int. Cl. D26—04

FIG. 1

FIG. 2

FIG. 3

FIG. 4

FIGURE 1 is a perspective view showing the front, one side, and the top of my new design for an electric battery lantern;

FIGURE 2 is a rear elevational view thereof;

FIGURE 3 is an elevational view of the side opposite to the one shown in FIGURE 1, and

FIGURE 4 is a bottom plan view thereof.

The dominant features of my design reside in the portions shown in full lines.

I claim:

The ornamental design for an electric battery lantern substantially as shown and described.
